UNITED STATES PATENT OFFICE.

JAMES HARVEY STRONG, OF STEUBENVILLE, OHIO, ASSIGNOR TO GILL BROTHERS COMPANY, OF STEUBENVILLE, OHIO, A CORPORATION OF WEST VIRGINIA.

DESIGN FOR A SHADE.

46,379.

Specification for Design.

Patented Sept. 8, 1914.

Application filed May 29, 1914. Serial No. 841,923. Term of patent 7 years.

To all whom it may concern:

Be it known that I, JAMES HARVEY STRONG, a citizen of the United States of America, and a resident of Steubenville, county of Jefferson, State of Ohio, have invented a certain new, original, and ornamental Design for a Shade, of which the following is a specification.

Referring to the drawings, the figure is an elevation of the shade in upright position.

The shade, referred to in a general way, is in the form of a pendant acorn, the top part 1 of the shade corresponding to the acorn cup and the lower portion 2 corresponding to the protruding end of the nut. Both the top and bottom portions 1 and 2 are fluted, the flutes 3 being in the vertical planes including the axis of the shade. Between the upper and lower portions is a convex, central zone 4 by which these portions are separated, this zone in effect forming the edge of the acorn cup.

A noticeable feature of the flutes is that the upper ends of those on the cup are con-

nected by looped portions 5, the upper ends of the flutes on the lower portion 3 of the acorn being similarly connected at 7.

I claim:

The ornamental design for shade in the form of a pendant acorn, the top part of the shade corresponding to the acorn cup and having a greater radius of curvature than the lower portion which corresponds to the protruding end of the nut, both the top and bottom portions being fluted, the flutes being in the vertical planes including the axis of the shade, the flutes on the upper and lower portions being connected in pairs by looped portions at their upper ends, the shade being formed with a central zone separating the upper and lower portions and in effect forming the lower edge of the acorn cup, substantially as shown and described.

Signed by me at Steubenville Ohio this 4th day of May, 1914.

JAMES HARVEY STRONG.
